CLAIM

The ornamental design for concealed door, cabinet and
frame assembly, as shown and described.

DESCRIPTION

FIG. 1 illustrates a forward perspective view of concealed
door, cabinet and frame assembly in accordance with the
present invention; and,

FIG. 2 illustrates a right, isometric rear perspective view of
concealed door, cabinet and frame assembly in accordance
with the present invention.

The broken lines depict portions of the concealed door,
cabinet and frame assembly that form no part of the claimed
design.
